UNITED STATES PATENT OFFICE

137,108

DESIGN FOR A MILITARY TOY TRUCK

Olai F. Larsen, Jr., Demarest, N. J., assignor to Prototype Corporation, New York, N. Y., a corporation of Delaware

Application September 30, 1943, Serial No. 111,244

Term of patent 7 years

To all whom it may concern:

Be it known that I, Olai F. Larsen, Jr., a citizen of the United States, residing at Demarest, in the county of Bergen and State of New Jersey, have invented a new, original, and ornamental Design for a Military Toy Truck, of which the following is a specification, reference being had to the accompanying drawings, forming part thereof, in which,

Fig. 1 is a plan view of a military toy truck
showing my new design,

Fig. 2 is a side elevational view,

Fig. 3 is a front elevational view, and

Fig. 4 is a rear elevational view.

I claim:

The ornamental design for a military toy truck, substantially as shown.

OLAI F. LARSEN, JR.
